UNITED STATES PATENT OFFICE.

DANA L. CHESTERMAN, OF PHILADELPHIA, PENNSYLVANIA, ASSIGNOR TO CHESTER-MAN-LEELAND CO., OF PHILADELPHIA, PENNSYLVANIA, A CORPORATION OF PENNSYLVANIA.

TRUSS PAD AND METHOD OF MAKING THE SAME.

Application filed July 29, 1926. Serial No. 125,649.

My invention relates to a new and useful truss pad, and the method of making the same, whereby more durable and lasting truss pads may be made and at a considerable saving of time, labor, and material.

It has been the practice in making truss pads heretofore, to secure a filler or core of resilient spongy rubber to a metallic form plate, and then to cover the rubber filler or core, as well as the metallic plate, with a layer of soft, pliable and waterproof leather. In so covering the truss pads with leather it was necessary to form a bead around the edge of the truss pad. This was done by a manual operation, that is, by taking a suitable beading material such as twine, rope or the like, laying the beading material around the edge, and sewing it together with the two leather plies. Due to this construction it was necessary to effect the sewing of the leather covers, by a manual operation, which consumed a considerable amount of time, and the result was not entirely satisfactory.

Moreover, it has been the practice, first separately to encase the sponge rubber filler or core, and the metal plate, in a cotton gauze material, and then securing the gauze-encased metal plate, to the flat back surface of the gauze-encased sponge rubber filler, by stitching together the gauze covers, around the peripheral edge of the metal plate. A piece of pliable waterproof leather of a size sufficient to cover the front of the filler, was then provided with a limp peripheral bead, by folding the edges thereof inwardly around a beading material and loosely stitching the turned-over edges of the leather, so as to encase the beading material therein. This front leather cover, having the limp peripheral bead encased loosely in the inturned edges thereof, was then applied to the filler, while a thicker back leather cover was applied over the metal plate. The limp beaded edge of the front leather cover was then stitched by hand to the edge of the back leather cover, throughout the peripheries thereof, thus completely enclosing the

gauze encased filler and metal plate in the front and back leather covers respectively. 50

The object of my invention is a truss pad of simplified construction, and one which may be assembled more quickly, and without any hand sewing or stitching, with a minimum number of parts, and a minimum number of operations.

Accordingly my invention contemplates the provision of a preformed and shape-retaining, relatively rigid bead, made by sewing or otherwise securing a beading material around the peripheral edge of a relatively rigid and form-retaining piece of fibrous material, such as sized burlap, buckramete or the like.

My invention further contemplates securing this beaded piece of form-retaining material to the flat base of a sponge, or other, resilient rubber filler or core, by adhesive or other means, applying the pliable and waterproof front leather cover over the front of the filler and folding the edges thereof over the pre-formed and shape-retaining bead and securing the same on the back of the burlap or bead-supporting sheet, by adhesive or other means. The metal plate is then superimposed upon the turned-over edges of the front leather cover, on the flat base of the filler pad, and secured thereto by adhesive or other means. A back leather cover, of the same contour as the metal plate, but slightly larger, is then superimposed upon the metal plate, and a row of stitches is passed through the overhanging edge of the back leather cover and through the beaded edge of the front leather cover, throughout the circumferences thereof, thereby completely encasing the filler and metal plate, to form a finished truss pad.

Due to my novel construction, this stitching operation can be carried out on any suitable sewing machine, thereby further eliminating manual operations, and thus reducing the time and cost of manufacture of the truss pads.

For the purpose of illustrating my invention I have shown in the accompanying

drawings several forms thereof which are at present preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the accompanying drawings, in which like reference characters indicate like parts.

Figure 1, represents a perspective view of form-retaining fibrous sheet, having the pre-formed peripheral bead; the first step in the making of my novel truss pad.

Figure 2, represents a section on line 2—2, Figure 1 on a slightly reduced scale, showing the manner in which the peripheral bead 20 is attached to the form-retaining fibrous sheet.

Figure 3, represents a perspective view of the moulded resilient sponge rubber core or filler, having the beaded form-retaining fibrous material adhesively secured to the flat back surface thereof, showing the second step in the making of my novel truss pad.

Figure 4, represents a section on line 4—4 of Figure 3 on a slightly reduced scale.

Figure 5, represents a plan view of the back of the truss after the front leather cover has been applied over the filler and the edges thereof folded back over the bead and adhesively secured to the form-retaining fibrous sheet; showing the third step in the making of my novel truss pad.

Figure 6, represents a section on line 6—6 of Figure 5, on a slightly reduced scale.

Figure 7, represents a plan view of the metal back plate.

Figure 8, represents a perspective view of the completed truss pad of my novel construction, having the metal plate applied to the back of the pad and having the back leather cover superimposed thereon and secured to the front leather cover by a peripheral row of stitches; showing the fourth and last step in the making of my novel truss pad.

Figure 9, represents a section on line 9—9 of Figure 8, on a slightly reduced scale.

By my novel construction I provide a suitable piece of relatively rigid and form-retaining piece of fibrous material 1, such a piece of sized burlap, buckramete or the like, and of the desired dimensions and contour and secure to the peripheral edge thereof a suitable bead 2, which may be formed of strands of cord or the like 3, encased in a suitable strip fabric 4, and sewed to the edge of the form-retaining material 1, by a row of stitches 5, as shown in Figures 1 and 2. By this means there is produced a form-retaining base 1, having at its edges a pre-formed bead, which will retain its shape

while being assembled and will permit the use of a sewing machine for the application of the stitches therethrough, since it is not necessary to hold the bead in shape during the final assembling operation.

To this beaded form-retaining base 1, I secure, by suitable adhesive, or other means, a filler or core 6, of suitable spongy or other resilient rubber 5, moulded or otherwise formed in the desired shape, and having the 75 back surface thereof flat, while the front thereof is suitably shaped. The flat back surface is placed upon the buckramete base 1, and adhesively secured thereto. The base, with the filler or core 6 applied thereto, is shown in perspective view in Figure 3, and in section, on a reduced scale, in Figure 4.

The next step is the application of the pliable and waterproof front leather cover 7, over the front of the rubber filler or core 6, and folding its edges around the bead 2 and in back of the buckramete or burlap base 1, and also adhesively securing the turned-over edges to the base 1, so as to retain the said front leather cover 7 fixed, while the truss pad is finally assembled. The folded-over edge of the outer leather cover 7 is designated by the numeral 8, and is shown more particularly on an enlarged scale in Figure 5.

I next apply the metal form plate 9, also of the desired contour and size, and of suitable thickness and rigidity, having suitable spaced and threaded apertures 10 and a suitable knob 11, by adhesively or otherwise securing it to the back of the burlap base 1, as shown in Figure 9. The back leather cover 12 is then applied to the assembly, over the metal plate 9, as shown in Figures 8 and 9, and the assembly is then ready for the machine stitching operation. A single or double row of machine sewn stitches 13, is then applied through the back leather cover 12, and through the front leather cover 7, within the inner periphery of the bead 2. This row of stitches passes inside the inner circumference of the bead 2 and completes the truss pad, by drawing the front leather cover 7 taut onto the rubber core or filler 6, and thus completely encasing the filler, base, and metal plate, in a leather cover.

It will thus be seen that by my novel construction and more particularly by the provision of the pre-formed, shape-retaining bead 2, mounted upon a shape-retaining fibrous backing material 1, I am enabled to produce a truss pad, without any manual or hand sewing, since the parts to be sewed together and thus secured, are retained in position, without any manual effort, while the stitches are applied. Moreover, by my novel construction I not only minimize the number of manual operations, but also reduce to a minimum the number of parts, by the elimination of the gauze casings about the filler

and metal plate, which were heretofore employed in truss pads.

It will now be apparent that I have devised a novel and useful construction of 5 truss pad and method of making the same which embodies the features of advantage enumerated as desirable in the statement of the invention and the above description, and while I have, in the present instance, shown 10 and described a preferred embodiment thereof of which will give in practice satisfactory and reliable results, it is to be understood that the same is susceptible of modification in various particulars without departing 15 from the spirit or scope of the invention or sacrificing any of its advantages.

Having thus described my invention, what I claim as new and desire to secure by Letters Patent, is:—

20 1. The hereindescribed method of making truss pads, which consists in forming a bead around the peripheral edge of a form-retaining sheet, placing a resilient filler pad on one side of said form-retaining sheet, applying 25 a pliable front cover over the filler pad, turning in the edges of said pliable cover around the bead and securing the same to the other side of said form-retaining sheet, applying a rigid plate to said 30 other side of said form-retaining sheet, applying a back cover over said rigid plate, and lastly fastening the front and back covers by a row of stitches passing through the peripheries of the two covers.

35 2. The hereindescribed method of making truss pads, which consists in sewing a bead onto one side of a form-retaining sheet, along the peripheral edge thereof, adhesively securing a resilient filler pad on one side of 40 said form-retaining sheet, seated within said bead, applying a pliable leather front cover over the filler pad, turning in the edges of said pliable front cover around the bead and adhesively securing the same to the other 45 side of the form-retaining sheet, applying the rigid plate to said other side of said form-retaining sheet, superimposed upon the turned-in edges of the pliable leather front cover, applying a back leather cover over 50 said rigid plate, and lastly fastening the front and back leather covers, by a row of stitches passing through the periphery of the back cover, and passing through the turned-in edge of the front cover and 55 through the front cover, around the inner periphery of the bead, thereby completely enclosing the filler pad, the form-retaining sheet and the rigid plate.

60 3. The hereindescribed method of making truss pads, which consists in forming a bead around the peripheral edge of a form-retaining sheet, by enveloping a suitable beading material in a suitable strip of fabric, and sewing the longitudinal edges of said strip 65 fabric to the peripheral edge of said form-

retaining sheet, placing a resilient filler pad on one side of said form-retaining sheet, seated within said bead, applying a pliable front cover over the filler pad, turning in the edges of said pliable front cover around the 70 bead and adhesively securing the same to the other side of said form-retaining sheet, applying a rigid plate to said other side of said form-retaining sheet, superimposed upon said turned-in edges of said pliable 75 front cover, applying a back cover over said rigid plate, and lastly fastening the front and back covers by a row of stitches passing through the periphery of the back cover, and passing through the turned-in edge of 80 the front cover and through said front cover, around the inner periphery of the bead, thereby completely enclosing the filler pad, the form-retaining sheet and the rigid plate. 85

4. In a truss pad, a resilient filler pad having a base, a pre-formed shape retaining bead secured to the peripheral edge of the base thereof, a flexible cover extending over the filler pad, a rigid plate superimposed upon the base of said filler pad, a cover 90 extending from said rigid plate, a row of stitches extending through the peripheral edge of said second cover and through said first cover, around the inner periphery of 95 said bead, fastening the two covers together, thereby completely encasing within them the filler pad, the pre-formed bead, and the rigid plate.

5. In a truss pad, a form-retaining sheet, having a peripheral bead thereon, a resilient filler member on one side of said sheet, a rigid plate on the other side thereof, a flexible cover extending over the resilient filler, a cover extending over the rigid plate, and a row of stitches extending around the inner 100 periphery of the bead, and through said two covers, thereby to secure the two to each other and to encase within them said filler, the form-retaining sheet and the rigid plate. 105

6. In a truss pad, a base sheet of relatively rigid material of predetermined contour, a preformed peripheral bead carried thereby, a filler pad on one side thereof, a metal plate on the other side thereof, a leather cover enclosing the filler pad and having its edges folded back over the base sheet, a leather cover extending over the metal plate, and a row of stitches extending through the two leather covers and around the inner periphery of the bead, securing the two leather covers together and enclosing within them, the filler, the base sheet and the metal plate. 115

7. In a truss pad, a form-retaining fibrous sheet having a peripheral bead in one side thereof, a resilient rubber filler pad seated within said bead and adhesively secured to said form-retaining fibrous sheet, and pliable leather front cover enveloping said pad and having its edges folded in, over said bead and adhesively secured to the other side of 125 130

said form-retaining fibrous sheet, a metal plate positioned upon said other side of said fibrous sheet, superimposed upon the turned-over edge of said front leather cover, a back leather cover, superimposed upon said metal plate, and a row of stitches passing through the peripheral edge of said back leather cover, the turned over edge of said front

leather cover and said front leather cover, around the inner periphery of said bead, ¹⁰ securing said two leather covers to each other, thereby completely encasing within them the filler pad, the fibrous sheet, the bead, and the metal plate.

DANA L. CHESTERMAN.
